CLOSURE FOR WASHING MACHINE
CYLINDERS

Hyman D. Brotman, Detroit, Mich., assignor, by
mesne assignments, to Horton Manufacturing
Company, Fort Wayne, Ind., a corporation of
Indiana

Application November 15, 1945, Serial No. 628,839

1 Claim. (Cl. 160—206)

1

The invention relates to washing machines and it has particular relation to a clothes receiving cylinder to be employed particularly in a washing machine of the automatic type.

In an automatic washing machine such as that embodied in my copending application for patent, Serial No. 573,362, filed January 18, 1945, the clothes receiving cylinder is supported at opposite ends for rotation about a horizontal axis. The driving unit includes means for rotating the cylinder first in one direction through a plurality of revolutions and then reversing the rotation so as to rotate the cylinder a plurality of turns in the opposite direction. Such movements are continued during the washing and rinsing stages. To enable inserting and removing the clothes, the side wall of the cylinder is provided with an access opening which can be closed by a door or closure for this purpose. The present invention may be considered as a continuation in part of such copending case and also of my copending case, Serial No. 543,538, filed July 5, 1944, which has matured to Patent No. 2,526,002, with respect to the cylinder.

One object of the present invention is to provide an improved type of clothes receiving receptacle or cylinder which may be manufactured inexpensively from sheet metal.

Another object of the invention is to provide an improved type of clothes washing receptacle or cylinder which is light in weight while still possessing the required strength and rigidity necessary to withstand the forces involved during operation of the washing machine.

Another object of the invention is to provide a clothes receiving receptacle having an improved type of closure for the opening through which the clothes are inserted and removed, wherein the closure may be quickly and easily opened through a folding movement thereof.

Another object of the invention is to provide an improved type of closure which may be positively locked in its closed position by locking means which may be easily released by the operator so as to permit the closure to be opened.

Other objects of the invention will become apparent from the following specification, from the drawings relating thereto, and from the claims hereinafter set forth.

For a better understanding of the invention, reference may be had to the drawings wherein;

Figure 1 is a plan view partly in cross section illustrating a clothes receiving cylinder constructed according to one form of the invention;

Fig. 2 is an end view of the cylinder as seen from the left end in Fig. 1;

2

Fig. 3 is an end view of the cylinder as seen from the right end in Fig. 1;

Fig. 4 is a cross-sectional view on a larger scale taken substantially along the line 4—4 of Fig. 2;

Fig. 5 is a cross-sectional view on a larger scale taken substantially along the line 5—5 of Fig. 3;

Fig. 6 is a view taken substantially along the line 6—6 of Fig. 4;

Fig. 7 is a cross-sectional view on a larger scale taken substantially along the line 7—7 of Fig. 1;

Fig. 8 is a fragmentary view on a larger scale showing a part of the closure and a locking means for holding the closure in closed position;

Fig. 9 is a fragmentary view of the locking means in its unlocked position;

Fig. 10 is a cross-sectional view taken substantially along the line 10—10 of Fig. 8; and,

Fig. 11 is a cross-sectional view taken substantially along the line 11—11 of Fig. 8.

Referring to Figs. 1 to 5, inclusive, the cylinder primarily comprises two semi-cylindrical bands 10 and 11 which are provided with outwardly directed mating flanges 12 and 13 at their longitudinal edges. These flanges are rigidly connected at longitudinally spaced points by spot welding indicated at 15, although it is evident that the flanges may be riveted if desired. The cylinder thus formed has inwardly pressed axially directed portions 16 at circumferentially spaced locations so as to provide radial baffles on the interior of the cylinder, and these baffles are useful in the clothes washing operation as they assist in carrying the clothes upwardly during rotation of the cylinder. Between the baffles the wall of the cylinder is provided with outwardly extruding and apertured projections 18 which are distributed generally over the cylinder wall to allow the water to freely enter and leave the cylinder.

As best seen by Figs. 2 and 4, the left end of the cylinder is closed by a generally concavo-convex disk 20 which at its outer margin has an axially directed flange 21 substantially fitting within the end of the cylinder wall. These fitting portions of the wall and disk are connected at circumferentially spaced points by rivets 22. Accurate location of the disk is effected by providing a circumferentially extending, inwardly directed bead 23 on the cylinder wall which engages the disk at the end of the flange 21, and this bead also acts to re-enforce the cylinder.

Also for the purpose of re-enforcement the outer portion of the disk is provided with radially directed pressed out beads 25, and it will be noted that the concave portion of the disk does not

extend entirely to its margin but terminates at a reverse bend 26. From the bend 26 to the outer marginal flange 21, the disk is radially directed as indicated at 27.

Inwardly of the beads 25, the disk is secured to a second disk 28 which centrally fits against the surface of the main disk. Outwardly of the fitting central portion, the disk has an axial rim 29 which joins a radially directed wall portion 31 and this wall portion in turn joins an outer concave flange 32 which fits against the principal disk and is welded thereto. A bearing support for a driving shaft includes a plate 33 which generally is of disk form and this plate 33 at its outer margin seats on the radial portion 31 of the second disk and is bolted thereto at circumferentially spaced points as indicated at 34. For the purpose of sealing the two disks together, the radial portion 31 of the second disk has an annular groove 35 in which a rubber sealing ring 37 is disposed, and this sealing ring is under compression between the plate and disk so as to prevent water from entering into the space centrally between the disks. The plate 33 at its center has an axially projecting hub 39 which is welded at opposite sides to a sleeve 40, and the latter serves as a support for a shaft supporting bearing 42.

The shaft, not shown, is adapted to extend through the bearing 42 and to have a spline engagement with a spline sleeve 43 which is welded to a disk 44. The latter fits between disks 46 and 47 projecting outwardly beyond the margin thereof and with particular reference to Figs. 4 and 6 together, the disk 46 has its outer margin welded to the disk 33 at a plurality of points as indicated at 50. Also the disk 46 at spaced points has recesses 51 formed by notching of the metal and at such recesses the outer portion of the disk 47 has bent over or offset tongues 52 which are disposed in the plane of disk 46 and also welded to the disk 33. This arrangement provides a space between the two disks 46 and 47 to accommodate the disk 44.

At spaced points, the disk 46 and disk 44 have openings 56 and 57 respectively for accommodating coil springs 58, and the disk 47 has corresponding pressed out portions 60 to accommodate such springs. Also it will be noted that the plate 33 is shaped to house the spring as indicated at 61. The construction provides pockets formed in disks secured to the cylinder and springs in said pockets while the openings in disk 44 enable the latter to compress the spring upon relative movement between the disk 44 and the other disks. Four springs are provided and it should be evident now that the driving connection between the spline sleeve 43 and end closure 20 of the cylinder is cushioned and that upon any reversing of the cylinder, the inertia forces may be cushioned through the springs.

The opposite end of the cylinder is closed by a concavo-convex disk 65 which has its marginal portion secured to the other end of the cylinder in the same manner as previously described in connection with the disk 20. This end of the cylinder is supported by a stub shaft 66 and the inner end of the stub shaft is mounted in a disk plate 67 having an outer marginal portion 68 welded to the central portion of the disk. The shaft is supported intermediate its ends by a third disk 69 having a marginal portion 70 welded to the disk 65. A supporting disk 71 is welded to the inner portion of the disk 69 and both of the disks 67 and 71 have hubs such as

indicated at 72, which may be welded to the shaft 66 or otherwise rigidly secured thereto.

The cylinder is provided with an opening in its side wall as indicated in broken lines at 73 in Fig. 8 so that clothes may be placed in the cylinder and removed therefrom. This opening is adapted to be closed by a closure generally indicated at 74 which includes two sections 75 and 76 hinged together by an ordinary piano type hinge 77. The section 75, as shown by Fig. 1, is hinged to the cylinder wall by a suitable piano type hinge indicated at 78 and it should follow, therefore, that the two sections may be moved from a closed position shown in full lines in Fig. 3 to an open position shown in broken lines in this figure. It may be noted at this point that the ends of both sections are shaped to provide beads indicated at 79, and this is desirable particularly in that it re-enforces the sections in a circumferential direction.

The closure is adapted to be locked in closed position by a locking means which includes oppositely movable bars 80 and 81 which project from opposite ends of a pan or housing 82, having side flanges 83 welded to the cover section 71. The ends of this pan are narrowed as indicated at 84 so that the bars are guided by such narrow sections, and intermediate its ends, the pan is widened and the two bars are angled so that their inner ends are disposed in spaced relation in a direction circumferentially of the cylinder. The inner end of the bar 80 has a notch 85 and the inner end of the bar 81 has a notch 86, and these notches respectively engage pins 87 and 88 projecting downwardly from a knob 90 as seen best in Fig. 7. Such knob is mounted on a central portion of the pan 82 and is turnably secured thereto by a pin 91 extending downwardly through an opening in the knob and which is secured to the upper wall of the pan by a cap screw 92. The pin 91 has a head 93 on its upper end which is disposed in an enlarged end of the opening in the knob and it follows that while the cap is secured to the pan, it is turnable thereon.

The lower part of the opening in the knob is enlarged as indicated at 95 and within this larger part of the opening a coil spring 96 is located. One end of this spring, as indicated at 97, is hook shaped and engages an opening 98 in the wall of the pan, while the upper end of the spring as indicated at 99, projects into a radial opening 100 in the wall of the knob. The arrangement is such that the spring normally tends to move the bars 80 and 81 outwardly and when the knob is turned clockwise, as seen in Fig. 8, to retract the bars, the spring resists this movement.

At their outer ends, the bars engage keepers which form part of a guide means for the closure and this structure now will be described.

With particular reference to Figs. 8, 10 and 11, the wall of the cylinder along opposite ends of the opening 73 is formed with circumferentially extending grooves 102 and 103, and these grooves respectively engage rollers 104 and 105 mounted on opposite ends of a shaft 106. This shaft extends through a curled bead 107 formed on the end of the cover section 76. Each of the rollers is retained in its groove by a guide element 108 having an overhanging portion 109 for substantially contacting the upper side of the roller, and this guide may be welded or otherwise suitably secured to the cylinder. It follows that in opening and closing the closure, the rollers will hold the end of the section 76 next to the cylinder wall 75 and due to the curved condition of the closure

sections, any upward movement of the section 76 as seen in Fig. 8 naturally will cause the sections to fold in the manner shown by Fig. 3.

Each of the bars 80 and 81 terminates in an upwardly offset end portion 111 which is adapted to project under the overhanging portion 109 of the guide 108 and with the bars positioned as seen in Fig. 10, the closure cannot be opened because the section 76 cannot move upwardly. For the purpose of re-enforcing the guide 108 over the ends of the bars, auxiliary bracket elements 112 are fastened to the guides 108, so as to provide a more rigid abutment or stop above the ends of the bars.

From the foregoing description with respect to the locking means, it should be evident that the knob may be turned so as to retract the bars from engagement with the abutments on the side guiding elements and that then the section 76 may be lifted by pulling upwardly on the knob. This lifting movement of the section 76 causes the sections to fold about the hinge 77 and at the same time, the rollers move along the guideways therefor which causes the sections to move into the positions shown by Fig. 3. After the clothes are removed or inserted as the case may be, the cover is closed and the knob is turned counterclockwise sufficiently to move the bars into locking position so that the cover will not accidentally become unlocked during operation of the washing machine.

The cylinder may be made out of an aluminum alloy or metal of similar light character and the metal may be anodized to prevent deterioration on account of soap, etc. Other metals may be employed in making the cylinder and may be coated with a suitable lacquer for preventing deterioration of the metal. Also the metal may be treated suitably if any additional treatment is necessary other than that mentioned above to

prevent the effects of electrolytic action such as may occur in the use of clothes washing solutions.

Although only one form of the invention has been illustrated and described in detail, it will be apparent to those skilled in the art that various modifications may be made without departing from the scope of the claim.

What is claimed is:

10 A closure for an opening in the cylindrical wall of a cylindrical container, comprising a pair of arcuate sections hinged to each other in end-to-end relation with the free end of one section hinged to said wall at one end of said opening, channel-shape guideways extending along the respective side edges of the opening, means on the free end of the other section projecting into said guideways to confine said end to the surface of said wall during opening and closing movement, a pair of bars mounted on one of said sections and circumferentially spaced from said means, said bars being movable parallel to the axis of the cylinder and engageable in the respective guideways to hold the sections against hinging movement, and means for simultaneously moving said bars into and out of locking position.

HYMAN D. BROTMAN.
